UNITED STATES PATENT OFFICE.

CURTIS J. ROTHERMEL, OF PHILADELPHIA, PENNSYLVANIA.

CRATE.

1,123,804.

Specification of Letters Patent.

Patented Jan. 5, 1915.

Application filed December 23, 1913. Serial No. 808,409.

To all whom it may concern:

Be it known that I, CURTIS J. ROTHERMEL, a citizen of the United States, residing at Philadelphia, in the county of Philadelphia 5 and State of Pennsylvania, have invented a new and useful Improvement in Crates, of which the following is a specification.

The primary object of my invention is to provide a construction of crate for shipping material in rolls, such as linoleum, oil cloth and roofing, wall and other paper, which requires to be protected against marring of its exposed surface, which is liable to such marring by rubbing against it of the sharp 15 edges of the slats in tightening them about the roll and while the package is in transit.

In the accompanying drawing, Figure 1 is a plan view of a section of crate-material constructed in accordance with my improvement; Fig. 2 is an end view of my improved crate bound about a roll of material to form a package thereof for shipment; Fig. 3 is a similar view of the same with the 20 heads omitted; Fig. 4 is a perspective view 25 of a broken section of one of the slats, showing its longitudinally-grooved inner face, and Fig. 5 is a perspective view of the members of the two-part head for each end of the crate.

To form my improved crate I fasten together in suitable spaced relation, preferably by means of sheet-metal bands 6 at 30 intervals, wooden slats 7 in desired length and width and of general rectangular cross- 35 section and having flat outer faces, to which the bands are riveted or nailed, but with their inner faces, or those which contact with the outer face of a roll 8 of linoleum, or the like, to be protected, longitudinally concaved, as shown at 9. The curve in cross-section of each concavity 9 is formed to fit more or less accurately the contour of the roll, so that those for crates to be used on rolls 8 varying materially in diameter, must 40 be formed differently, as to their curves in cross-section, to conform to the different arcs presented by the various contours of the rolls. To form a package of a roll 8 for shipment, a section of the crate-material, 45 such as is represented in Fig. 1, is wrapped around the roll and the bands are riveted together or otherwise fastened at their overlapping ends. The bands are secured inter-

mediate their ends to the flat outer surfaces of the slats 7. These flat bands are preferable to the round-wire form thereof for binding the package, since such wires cut into the slats, thereby loosening the confinement of the roll and permitting the latter to be shifted about in the crate with liability to resultant injury from rubbing against the inner corners of the slats.

Where the package is required to be headed, I provide on each end a head 10 formed of two similar wooden blocks 11 and 12 with their ends rounded to conform to the curve of the slat-grooves and recessed, as shown in Fig. 5, crosswise of the grain of the wood on their opposing faces to strengthen them and prevent warping. 15 These head-sections are nailed together crosswise with their recessed faces interfitting, and the slats fit at the groove-sections 20 of their end-portions against the convexly-curved ends of the head-members, to which 25 they are fastened, as by nailing.

Besides the advantage referred to of my improved crate-construction, in preventing the surface of the contained roll from becoming marred by conforming to the cylindrical shape of the roll, the width and weight of the package are reduced to the minimum, which adapts it to take up less room and weigh less in shipment than the ordinary crate of rectangular cross-section, 30 thereby economizing materially in the expense of transportation. Moreover, since the general rectangular shape in cross-section of each stave is not changed by concaving it along its inner face, it is not weakened thereby, so that my improved crate is 35 equally as strong as the ordinary crate and is devoid of its disadvantages.

What I claim as new and desire to secure by Letters Patent, is:—

1. A crate for material in a roll, comprising a plurality of spaced slats, bands connecting said slats, the outer, side and end faces of said slats being plane, and the inner faces of said slats concaved to conform to 40 and fit against the outer cylindrical surface of the roll.

2. A headed crate for material in a roll, comprising a plurality of spaced, band-connected slats having flat outer surfaces and 45 having their inner faces longitudinally con-

caved to conform to and fit against the portions covered by them of the outer surface of the roll, and heads each formed of a pair of crossed wooden blocks recessed and interfitting at the recesses in their opposing faces at which they are secured together, and having their outer faces disposed in the same

plane, said blocks having curved ends against which the concaved end-portions of the slats fit and are fastened.

CURTIS J. ROTHERMEL.
